UNITED STATES PATENT OFFICE.

FRANK ZOERKLER, OF FRYBURG, PENNSYLVANIA.

GATE OPENING AND CLOSING MECHANISM.

1,111,282.

Specification of Letters Patent.

Patented Sept. 22, 1914.

Application filed August 1, 1913. Serial No. 782,401.

To all whom it may concern:

Be it known that I, FRANK ZOERKLER, residing at Fryburg, in the county of Clarion and State of Pennsylvania, have invented 5 certain new and useful Improvements in Gate Opening and Closing Mechanism, of which the following is a specification.

My invention, which relates generally to the class of farm gates, railway crossing gates, mine doors and the like, primarily has 10 for its object to provide a simple, inexpensive and effectively operating means whereby the gates or doors may be conveniently opened or closed by the occupant of a vehicle or horse, through the medium of hand actuated levers, without dismounting, or mechanically operated, by reason of contact of 15 the passing vehicle with lever devices that act to first unlock the gate or door and then 20 swing the door, the operation of closing the door being likewise effected.

My invention further comprehends certain 25 improved arrangement of parts, in a gate or door actuating means of the general character stated, including automatically operable devices for holding the door to its outwardly or inwardly swung positions.

With further objects in view that will be 30 later stated, my invention consists in the peculiar combination and novel arrangement of the parts hereinafter fully described, specifically pointed out in the appended claims and illustrated in the accompanying drawings, in which:

Figure 1 is a perspective view of my invention, the operating mechanism being especially adapted for farm gates and for 35 being manually operated, the gate being at the closed position. Fig. 2 is a similar view, 40 the gate being shown at the swung back or open position. Fig. 3 is a detail view of a rockable crank lever, that serves as a substitute for the hand controlled levers shown in Fig. 1, to thereby adapt my gate opening 45 and closing devices for being actuated by the wheel of a passing vehicle. Fig. 4 is a detail view of the gate latch releasing devices, hereinafter specifically explained. Fig. 5 is a detail perspective view, parts being in section, of the rotary pulley or wheel. Fig. 6 50 is a perspective view of a railway gate with my opening and closing mechanism co-operatively connected therewith, the said mechanism being a modification of that shown in 55 Figs. 1 and 2, to render it especially applicable for being actuated by the car wheels of

an approaching train, the gate being at the open position. Fig. 7 is a perspective view of the mechanism shown in Fig. 6, the gate being at the closed position. Fig. 8 is a detail perspective view of the sector member that is a part of the power transmission that oscillates the rotary pulley or wheel. Fig. 9 is a detail edge view of the rotary pulley or wheel hereinafter again referred to. 60 65

In the practical application of my gate or door opening and closing mechanisms, the several parts that constitute the complete mechanism include actuating lever devices located at each side of the gate or door, 70 so that after opening the gate or door, the said gate or door may be readily closed either manually or mechanically.

When my invention is to be utilized for opening and closing farm gates, the parts 75 are arranged in the manner best shown in Figs. 1 and 2, of the drawings, by reference to which it will be noticed the gate 1, which is hinged to swing in the horizontal plane, is joined to the hinge post 2 80 with which connects a short section of fencing 3.

4 designates a bracket that includes the outwardly extended V-shaped upper and lower sections 40—40, the apex portions of 85 which form bearings 41—41 for a short stub shaft 43, that passes through the hub 5, of what I term, a rotary wheel or pulley 6, since it is through the reverse rotations or oscillations of the said pulley that the 90 gate is swung on its hinges to the open and closed positions.

The pulley 6, which has a deep groove, has wound about it, a pair of operating cables 7—7, they being so wound, and connected, by the screw eyes 8, with the pulley that a pull strain effected by lever devices (presently explained) at one side of the gate tends to rotate the pulley 6 in one direction, while a pull strain on the said 100 cables from the other side of the gate causes the pulley to rotate in a reverse direction.

For operating the cables 7—7, either the hand lever devices shown in Figs. 1 and 2 may be used, and when they are to be operated mechanically the crank lever devices shown in Fig. 3 are employed. When arranged as in the said Figs. 1 and 2, a vertically disposed hand lever 9 is fulcrumed on a support 10, some distance in advance 110 of the gate (it being understood, that a lever 9 is located along the roadway at each

side of the gate), and to the said levers are connected the cables 7-7, one above and the other below the fulcrum point.

11-11 are turn buckles for regulating the tension of the cables 7.

5 Coöperatively connected with each lever 9 is a third lever 12, the latter being pivotally joined to the lever 9, and it includes a hand portion adapted to be closed up 10 against the handle end of the said lever 9, it being normally swung back by the coiled spring 13.

14 designates a wire cable, one end of which connects with the lower end of the 15 lever 12, and the other end to a bell crank lever 15 horizontally mounted in a bracket 16 secured to the hinge post 2, the short arm 15^a of which engages a roller stud 17 mounted in the bifurcated head 18 of a 20 pull rod 19 slidably mounted in the bracket 16 and whose outer end terminates in an eye 19^a. Rod 19 is held to its normal position by a coiled spring 20.

21 designates a pivoted crank latch on 25 the free end of the gate, 22, a flexible rod that joins the latch with the eye of the rod 19 and 23 designates a turn buckle on the rod 22 for taking up slack.

30 By reason of arranging the latch devices as shown, when the operator grasps the hand lever for opening the gate, he first closes the lever 12 against the lever 9, and thereby pulls the latch up to unlock the gate before he moves the lever 9 to swing 35 the gate.

23^a designates a bail, the ends of which are turned inwardly and fastened to a metal plate 24 secured to one of the gate bars; and 24^a designates a roller bearing 40 that rides within the said bail and which is mounted on a short stud shaft, the ends of which are made fast to the pair of horizontally disposed strap iron bars 25 that extend diagonally inward from the rotary 45 pulley 6 to the upper and lower faces of which the said bars 25 are secured.

26 designates a stout coiled spring, the upper end of which is adjustably secured to a bracket 27 on the fence structure. The 50 spring extends diagonally over the pulley 6 and carries at its outer end, a grooved roller 28 that engages a hold-back or cam device on the pulley that consists of a stout rod frame composed of legs 29-29 that 55 merge with a horizontal loop-like portion 30, the said hold-back and the spring pulled roller that engages it, being so arranged, relatively to the axis of the pulley 6, that when the gate is closed it is held to that 60 position and when opened it is likewise held to that position under spring tension. The member 30 is so located on the pulley 6 and is so formed that it will aid the final opening and closing movement and also 65 serves to retain the gate in either the open

or closed position under tension of the spring 26.

31 indicates the stop post, provided with a buffer spring 32 to take up the shock when the gate is swung back to its open 70 position.

When my invention is to be utilized for swinging railroad gates or for mechanically closing farm gates, the modified construction shown in Figs. 6, 7 and 8, is employed. 75 In this latter form, the same general means for swinging the gate shown on Sheet 1 of the drawings, is provided, the differences in the complete construction existing in the means for transmitting the mechanically 80 applied power to the pulley 6 that swings the gate. In the said modified form in place of the hand operated levers 9, is substituted a vertically disposed grooved wheel 60 provided at one side with a gear segment 85 61 that meshes with a toothed quadrant 62 mounted in the shaft 63 on the outer end of which is a crank trip 64 disposed adjacent to the track to be engaged by the wheels of the passing engine and which is normally 90 turned to the upright position by the stout coiled spring 69 held on the said shaft. The shaft 63 also has a cross pin 65 that engages a slot 66 in the quadrant to cause it to return to normal after the gate has been 95 set. When the modified form just described is utilized for farm gates, the cross pin 65 (see Fig. 3) forms a substitute for the lever 9, shown in Fig. 1. The cables 7-7 in this latter form of my invention pass 100 over and are secured to the toothed turning wheel 60, so that as the said wheel is reversely rotated the reverse pull on the cables is effected for actuating the opening and closing pulley 6.

105 From the foregoing description taken in connection with the drawings, the complete construction, the operation and the advantages of my invention will be readily understood by those skilled in the art to which it appertains.

110 While for practical purposes I prefer to arrange the details of structure substantially as shown in the drawings, I desire it understood that the said details may be materially modified or changed to suit the special requirements for my door closing and opening mechanism without departing from the scope of the appended claims.

115 What I claim is:

1. In a gate opening and closing mechanism, a fixedly held bracket, a rotatable pulley carried on the bracket and provided with means for connecting with a gate, operating cables connected with the pulley for 120 rotating it in opposite directions, means including a coil spring connected with the bracket and the pulley to assist in the final movement in turning the pulley to open and close the gate and to hold it to its open and 125 close position under tension of the spring.

130

closed position, the said means further including a shiftable connection between the spring and the pulley.

2. In a gate opening and closing mechanism, the combination of a horizontally disposed rotatable pulley, a member pivotally connected to the pulley and adapted to be slidably connected to the gate, cables that take around and are made fast to the pulley for imparting reverse motion thereto, a horizontal loop having stop members at the opposite ends fixedly mounted on the rotatable pulley, a spring fixedly secured at one end and having its free end extended over the pulley and provided with a bearing member at the outer end that rides on the loop as the gate moves to the opening or closing direction and engages with the end bearing members of the said loop whereby to hold the gate to its opened and closed position under spring tension.

3. In a gate opening and closing mechanism, a longitudinally extended bail adapted to be mounted on the gate, a horizontally mounted rotatable pulley, brackets projected from the gate framing on which the pulley is mounted, arms secured to the pulley that project diagonally inward toward the gate, the free end of the arms straddling the bail on the gate and a roller carried between the free ends of the arms for engaging the bail, means operable from the roadway at either side of the gate for rotating the pulley in reverse directions to thereby swing the roller that engages the bail on the gate to open or close the gate, and other means controlled by the reverse movements of the

aforesaid pulley for holding the gate to its closed or open positions under spring tension, said other means including a member projected above the pulley, and having a curved portion, a spring and a movable connection between said spring and said curved portion, said curved portion having its ends arranged eccentric to the axis of the pulley and adapted to coöperate with said spring to assist in the final opening and closing movement and also serve to retain the gate at either the open or closed position.

4. In a gate closing mechanism, a swingable closure member operating mechanism comprising a rotatable pulley, a movable connection between the pulley and the closure member, a longitudinally extended bail on the closure member with which the traveling connection operates, means for reversely rotating the pulley to thereby swing the gate to its open and closed position, means for holding the closure member to either its closed or open position under spring tension, the said means consisting of a member mounted on the pulley and including a horizontal loop disposed tangentially with respect to the axis of the pulley, a coil spring that extends diagonally over the pulley, one end of which is made fast to the framing on which the closure member is hinged, and a grooved roller on the other end of the spring that engages the loop of the member.

FRANK ZOERKLER.
